SPRING HAMMER

Filed Aug. 27, 1929

UNITED STATES PATENT OFFICE

RUSSELL C. BOWEN, OF SEATTLE, WASHINGTON, ASSIGNOR OF ONE-HALF TO GEORGE R. KOLLOCK, OF SEATTLE, WASHINGTON

SPRING HAMMER

Application filed August 27, 1929. Serial No. 388,664.

This invention relates to electrically controlled spring hammers, and has for an object the provision of improvements in hammers of this type whereby the device is rendered more convenient and efficient in its operation. Another object of the invention is the provision of means, in combination therewith, whereby the device may be used either for a hammer or a power drill, selectively. With the foregoing and other objects in view, the nature of which will become apparent, the invention consists in the novel construction, arrangement and combination of parts hereinafter described and claimed.

In the drawing, Figure 1 is a vertical view partly in section of an embodiment of the present invention, parts being shown in side elevation and the hammer die or tool indicated by dotted lines. Figs. 2 and 3 are transverse horizontal sections, taken substantially on the lines 2—2 and 3—3, respectively, of Fig. 1; Fig. 4 is a horizontal vertical section, through 4—4 of Fig. 1; and Fig. 5 is a detail view of the rotor and hammer members shown in Fig. 1, and indicating the relative positions of the aforesaid members preparatory to the release of the spring-impelled hammers.

Reference being had thereto, the numeral 5 represents, generally, a casing, desirably formed to provide a depending tubular portion 7, offset from the axial line set up in a shaft housing 8, communicating therewith. Said casing also includes a portion 9 secured as by bolts 10 to form a rigid and integral part, and is adapted to house therein a motor 11, and suitable geared driving mechanism, hereinafter described.

As illustrated, the aforesaid tube casing portion 7 is arranged to have disposed, axially therein, a cylindrical striking member or hammer 12, guided by a bearing 13 provided in the floor 14 of the housing 8, and by a collar 15, screw threaded upon the projecting nipple 16 of said hammer, acting in the bore 17 of

such casing portion. I also provide in the upper and lower extremities, respectively, of said tube casing 7, vent holes 25 and

50. Sleeved within the projecting end of said

casing portion 7, and provided with an annular flange 18 arranged for seating engagement with said portion extremity, is a head piece 19, within which is an adjustable screw threaded bushing nut 20 in which operates the shank of a suitable hammer die or tool 21.

Arranged to be inserted between said bearing 13 and the casing floor 14, is an annular ring member 22, secured in rigid engagement therebetween through suitable flange bolts 23, and is desirably provided with a plurality of spring engaging inwardly projecting radial finger elements 24 (Fig. 3).

Reference being had to Figs. 1 and 3, the aforesaid tubular portion 7 is adapted to receive, surrounding the hammer 12, a pair of complementary annular compression springs 26 and 27, hereinafter termed the major and minor springs, respectively.

Said major spring is clamped between the aforesaid fingers 24 and the bearing 13 to have the lower flute 28, thereof, in spaced apart relation above the hammer collar 15, the minor spring being arranged interiorly thereof and in spring pressed engagement between the opposing secured hammer collar and said bearing 13.

The described spring structure allows the hammer and its associated collar to have successive impulses imparted thereto, the major spring providing an effective highly compressed kicking action, whereupon the minor spring asserts its continuation of the blow, to effectually eliminate undue shock, and allowing of a ready retraction in compressing the successive springs.

The end of the striking member within the chamber 8 is slotted longitudinally, as at 29, to afford two bifurcations 30, which are bored transversely to receive a pin 31, upon which is mounted, within the slot 29, a roller 33. Guide rods 31 cooperating with tracks 32 of said arms 30, eliminate lateral thrust to the aforesaid bifurcated arms.

85 represents a shaft which extends through journal bearings 34, provided in the end walls of the casing, and is driven through suitable means represented as a gear wheel 36 meshing with a pinion 37, having its shaft carried in the head piece 38 of said casing 8, and actu-

ating the aforesaid hammer die 21. The aforesaid gear wheel 36 is mounted on a shaft 39, which is secured to a frame 40, and is supported by a bearing 41, and is driven by a motor 42.

ated by a suitable reduction gear 39 meshing with the driven pinion 40 of the motor.

As shown, said motor is suspended in suitable standards of the casing portion 10 and is controlled through a finger switch 41 of a handle 42, integral with said portion 10.

Reverting to the aforesaid shaft 35, I provide a centrally located integral rotor 43, having substantially intermediate of its width, a diametrically disposed slot 44, within which, for limited longitudinal movement, is a gravitationally propelled slide bar 45. Said slide, furthermore, in restricting such movement, is engageable, in a slot 46 thereof, with a set screw 47 of the rotor, and as such, provides a medium whereby said slide is actuated in reciprocatory movement, resultant of the rotative movement of said rotor to position said slide into lifting engagement with the roller 33 of said bifurcated hammer portion.

It will be readily understood from the foregoing, that the hammer is afforded a succession of two blows per rotor revolution.

The effective impulse of the hammer against the die is adjustably regulated through the medium of the heretofore described bushing nut 20, the faced position thereof being preferably knurled to facilitate ready selective rotative adjustment by an operator.

In combination with the foregoing hammer structure, I have provided, axially of the shaft 35, an interiorly screw threaded exposed hub portion 48 (Fig. 4) arranged to take the projecting threads of a drill tool (not shown) whereby the utility of the device is enlarged to encase drilling operations.

The operation of the striking member is as follows:

Closing switch 41 affords a current of electrical energy to actuate the motor, rotating pinion 40 to drive the gear wheel 36 and the rotor 43 carried thereby.

The rotor thus driven gravitationally drops slide 45 through its slot 44 and acts to impart, through revolution thereof, elevational movement to the roller 33, whereby helical springs 26, 27 are successively compressed.

As the slide progresses in its revoluble movement, the roller 33 spins on its axis 31 and imparts a force cooperative with the gravitational pull to retract in disengagement therefrom the aforesaid slide 45 to the position shown by dotted lines (Fig. 5). The roller and striking member becoming unsupported thereby, cooperative successive spring momentum is afforded to effect a striking blow of the hammer against the tool.

Revolution of the slide, cooperating with the springs, produces intermittent reciprocatory motion to the hammer.

It is to be noted that a substantially vertical or axial application of retractive force

is applied to the hammer member, lateral thrust being obviated through the roller arrangement and guide rods.

The construction, arrangement and operation of parts is believed clear from the foregoing, it being obvious that numerous changes might be resorted to within the scope of the appended claims.

What I claim, is:

1. In apparatus of the class described comprising a cylinder having a vertically adjustable bushing secured in its outer end, a tool slidably engaging therein, a housing communicating with said cylinder and having a bearing secured to the floor portion thereof, a reciprocating striking member in the cylinder having a slotted upper end extending through said bearing into the housing, complementary springs in said cylinder for driving the striking member against the tool, one of said springs being secured in depending relationship from said bearing, the other of said springs being arranged in opposing relationship between said bearing and a collar secured to said member, a driven rotor and a slide for said rotor arranged for longitudinal gravitational movement in a slot thereof and adapted to rotate through the slotted end of the member to continuously impart intermittent retractive movement to said striking member in opposition to said springs.

2. In apparatus as defined in claim 1, wherein means are provided in said rotor and said slide for restricting the longitudinal gravitational movement of said slide.

3. In apparatus of the class described comprising a cylinder having a vertically adjustable bushing secured in its outer end, a tool slidably engaging therein, a housing communicating with said cylinder, a reciprocating striking member in the cylinder having a slotted upper end extending into said housing, a rotor, a slide for said rotor arranged for limited gravitational movement in a slot thereof and adapted to rotate through the slotted end of the member to impart intermittent retractive movement thereto, a motor for continuously driving said rotor, and spring means acting in opposition to said rotor retractive action and adapted to impart striking movement to said member against said tool.

4. A hammer of the class described comprising a striking member, a cylinder for said member, a collar secured to the lower portion of said member and arranged for vertical movement in said cylinder, a bearing, the upper portion of said member extending through said bearing, a rotor, a gravitationally propelled slide in said rotor, a roller carried by said striking member and engageable by said slide to retract said striking member, and means acting in opposition thereto to effect intermittent striking motion

to said member in the opposite direction to said retractive movement.

5. In apparatus of the class described, a casing, a bifurcated striking member arranged for reciprocatory axial movements, a roller carried by said member in the opening between the bifurcations thereof, a rotor, means to drive said rotor, a gravitationally propelled slide for said rotor arranged for 10 longitudinal movement in a slot thereof, said slide being adapted to act against said roller for imparting axial motion to said striking member in one direction, and spring means acting in opposition to said slide movement 15 for imparting axial motion to said member in the opposite direction.

6. In apparatus as defined in claim 5, a shaft for said rotor journaled in end walls of the casing and having an exposed portion 20 at one end thereof, said exposed portion being adapted to engage the shank of a drill in a manner to impart rotative movement thereto.

Signed at Seattle, Washington, this 3rd
25 day of August, 1929.

RUSSELL C. BOWEN.
